A. G. ROTINOFF.
PILE DRIVING APPARATUS.
APPLICATION FILED JUNE 17, 1921.

1,391,344.

Patented Sept. 20, 1921.

UNITED STATES PATENT OFFICE.

ALEXANDER GEORGIEVITCH ROTINOFF, OF LONDON, ENGLAND.

PILE-DRIVING APPARATUS.

1,391,344.

Specification of Letters Patent. Patented Sept. 20, 1921.

Application filed June 17, 1921. Serial No. 478,308.

To all whom it may concern:

Be it known that I, ALEXANDER GEORGIEVITCH ROTINOFF, a Russian citizen, residing at London, England, have invented certain new and useful Improvements in Pile-Driving Apparatus, of which the following is a specification, and for which I have filed an application, No. 11,113, in Great Britain, on April 21, 1920.

10 This invention is for an improved method and means for driving hollow piles or effecting like operations, and has for its object to enable hollow piles, or other tubular structures, especially those of considerable length, 15 to be driven or sunk more efficiently than is at present possible. If piles are driven by a monkey operating upon the bottom of the pile at the back of the nose there is a tendency for the tubular sections of the body 20 portion of the pile to become dislocated or fractured, by reason of the retarding effects of friction at the sides and also the inertia of the main body of the pile. On the other hand, if the blows are applied to the upper 25 end only, the same retarding forces tend to cause the body portion of the pile to crumble, or its sections to become dislocated. Again, the "spring" in the length of tubing is considerable, and this greatly reduces the 30 effectiveness of the blows, whether they are applied solely to the lower end or solely to the upper end of the pile.

According to this invention apparatus for driving a hollow pile or like hollow structure by blows applied at different points simultaneously comprises two separate monkeys, one mounted within the hollow structure immediately at the back of the nose of such structure and the other at the top of 40 the structure, and means involving in itself a comparatively small inertia effect, for example a cable, for connecting the two monkeys whereby the two monkeys may be raised and lowered as one.

45 It will be appreciated that a long rigid member extending from the bottom monkey to a point where it would have contact with the upper monkey would have disadvantages owing to the fact of its inertia and 50 spring, and if the inertia effect were overcome by rigidly securing it to the upper monkey, the disadvantages of a spring of a long member would still remain.

Preferably, both of the monkeys and the

means for raising them (for example, a 55 fixed member, such as a piston constituting one part of a vertically operating cylinder and piston) are carried bodily upon the structure to be driven so that the useful weight of these parts is at all times operative upon the pile. The connection between the two monkeys may be provided with means of adjustment, for example a spring and one or more adjusting nuts for a rod or rods comprised in such connection. 60

The lower monkey may take the form of a solid block of material, but the upper monkey may be made hollow to constitute a cylinder for a fixed piston.

65 In the accompanying drawings— 70

Figure 1 is a central vertical section through the apparatus constructed according to one method of carrying out this invention;

75 Fig. 2 is a central vertical section through the apparatus constructed according to another method of carrying out this invention, and

Fig. 3 is a transverse section through the apparatus on the line 3—3 of Fig. 2. 80

85 In the construction shown in Fig. 1, the driving tube A is operated upon by a monkey B within the tube, which strikes the back of the nose B¹ of the tube and is also operated upon by a monkey C which strikes the top of the tube. The nose B¹ is screwed into the tube A in the usual manner, and has a shoulder B³ against which a surrounding ring B⁴ bears. The object of this ring B⁴ is to provide a wider opening than that afforded by the nose B¹ itself, and to accommodate a casing-tube hereinafter referred to so that the driving-tube A with the nose B¹ secured to it can afterward be bodily withdrawn leaving the ring B⁴ and the casing-tube *in situ*. 90 The upper end of the driving-tube carries a cap D to which is secured a centrally-arranged piston D¹. The piston is carried by a hollow rod D² from the cap D, and the monkey C is made hollow to constitute a 100 cylinder for this piston. Steam is admitted at E to the interior of the cylinder by a flexible conduit indicated in chain-line at E¹. The cylinder carries a centrally-situated rod F whose lower end is connected to the monkey B by a cable F¹ and this rod extends through a downwardly directed 105 guide-tube C¹ on the cylinder which has slid-

ing connection with the piston D¹ by way of a stuffing-box.

Outside the driving-tube A is a casing-tube G which is driven from its upper end by means of a collar G¹ placed between it and the cap D which rests on the driving-tube A. The lower end of this casing-tube rests on the ring B⁴ and thus the casing-tube assists in driving the ring forward.

- 10 The cable F¹ is so adjusted by means of a spiral spring H and nuts H¹ at the top of the rod F, that if the monkey C is raised by the admission of steam through the port E, the monkey B of course being raised with it, 15 both monkeys will strike their respective supports as they descend when the steam is exhausted by way of the port E. Any means may be provided for controlling the inlet and exhaust of the steam.
- 20 It will be seen from the above that the pile receives simultaneous blows at different points, namely at the bottom by the monkey B and the top by the monkey C, or the adjustment could be so arranged that these 25 blows instead of falling simultaneously succeed one another rapidly.

It will be seen from the above description that the monkey B drives the nose of the pile forward, and the stress which would be 30 put upon the body of the pile by this action is relieved by the operation of the upper monkey C which drives the tubular body part forward at the same instant as the nose is driven forward when the blows are arranged to operate simultaneously. The upper monkey C has only to apply sufficient 35 force to the pile to cause the body portion to overcome the inertia of the said body and the resistance offered by friction so that it 40 does not tend to crumple the pile or dislocate the various sections of which it may be composed, in the same manner as it would if it had to overcome the said inertia and friction and also had to drive the nose B¹ 45 forward.

If desired, the driving-tube A with all the driving apparatus could be removed when the necessary depth has been reached, and the exterior casing G with the nose B¹ 50 alone left *in situ*.

In some cases it may be preferred to so arrange the upper monkey that the flexible tube E¹, or other tube supplying the steam, need not be movable with the monkey. 55 Such an arrangement is shown in Figs. 2 and 3 where the pile-driving tube J is provided with a nose J¹ as before and carries a cap J² as before, but the fixed piston K instead of being carried from the cap J² is 60 made to depend from the upper portion of a skeleton frame K¹. Steam is admitted by a fixed conduit K² to the interior of the fixed piston K and escapes thence into the chamber provided for it in the movable cylinder 65 L. This chamber is formed in a downward

extension L¹ of the cylinder and the steam operates to thrust the cylinder upward until the exhaust is opened to the interior of the piston K, for example, by a hand-operated valve K³. The bottom part of the 70 extension L¹ is provided with ports L² to allow free ingress and egress of air.

To connect the movable cylinder of upper monkey L with the lower monkey M a double cable M¹ is provided which is looped 75 around a pulley M² carried by the monkey and spring-controlled as at M³ and has its free ends connected to rods M⁴, one on each side of the extension L¹ of the cylinder. These rods extend through the cap J² and 80 the upper portion of the cylinder L and are carried by springs M⁵ and nuts M⁶. These nuts can be adjusted to regulate the operative length of the cable M¹ so that simultaneous blows may be struck by the monkeys L and 85 M if desired. To prevent the cylinder L from rotary movement, it is provided with jaws L³ which engage inwardly-directed webs K⁴ on the upper members of the frame K¹.

90 The upper part of the pile-tube J may be strengthened by a split collar J⁵ placed around it, and provided with ears J⁶ whereby the two halves can be clamped together. Such a collar could also be employed instead 95 of the collar G¹ in Fig. 1.

It will be noted that in the construction of pile driving apparatus described, both monkeys are at all times supported by the pile which they are driving so that their 100 useful weight is at all times operative upon the pile.

Obviously, the invention is not restricted to the driving of piles, as it can be equally well applied to the sinking of bore holes or 105 wells, means being provided within the hollow structure to receive the blows of the bottom monkey.

What I claim as my invention and desire to secure by Letters Patent is:—

110

1. For driving tubular structures into the soil, the combination of, a tubular member, a tapered nose at the lower end thereof having driving connection with the tubular member, a monkey guided to rise and fall in an 115 approximately vertical path and in falling to strike the top of the tubular member, a second monkey within the tubular member and immediately behind the nose of the same, means for causing the upper monkey 120 to rise and to be dropped alternately on to the top of the tubular member, and non-rigid means having in itself a comparatively small inertia effect connecting the lower monkey to the upper monkey, whereby the 125 lower monkey is made to follow the movements of the upper monkey.

2. For driving tubular structures into the soil the combination of, a tubular member, a tapered nose at the lower end thereof hav- 130

ing driving connection with the tubular member, a monkey guided to rise and fall in an approximately vertical path and in falling to strike the top of the tubular member, a second monkey within the tubular member and immediately behind the nose of the same, means for causing the upper monkey to rise and to be dropped alternately on to the top of the tubular member, and 10 flexible means, that is a cable or chain, connecting the lower monkey to the upper monkey whereby the lower monkey is made to follow the movements of the upper monkey.

3. For driving tubular structures into the soil, the combination of, a tubular member, a tapered nose at the lower end thereof having driving connection with the tubular member, a monkey guided to rise and fall in an approximately vertical path and in falling to strike the top of the tubular member, a second monkey within the tubular member and immediately behind the nose of the same, means for causing the upper monkey to rise and to be dropped alternately on 20 to the top of the tubular member, non-rigid means having in itself a comparatively small inertia effect connecting the lower monkey to the upper monkey, whereby the lower monkey is made to follow the movements of the upper monkey, and means for adjusting the effective length of the connection between the two monkeys.

4. For driving tubular structures into the soil, the combination of, a tubular member, a tapered nose at the lower end thereof having driving connection with the tubular member, a monkey guided to rise and fall in an approximately vertical path and in falling to strike the top of the tubular member, a second monkey within the tubular member and immediately behind the nose of the same, means for causing the upper monkey to rise and to be dropped alternately on 40 to the top of the tubular member, non-rigid means having in itself a comparatively small inertia effect connecting the lower monkey to the upper monkey whereby the lower monkey is made to follow the movements of the upper monkey, and a screw-threaded rod for the upper end of the connecting means having on it an adjusting-nut and a spring operating between the nut and a supporting part of the monkey whereby adjustment of the operative length of the 50 connection can be made.

5. For driving tubular structures into the soil, the combination of a tubular member, a tapered nose at the lower end thereof having driving connection with the tubular member, a monkey comprising a cylinder-element and a piston-element, one of these elements being fixed on the top of the tubular member and the other sliding on it and constituting an upper monkey to strike the 60 top of the tubular member, a steam-pipe

connected to one of the elements to admit steam to effect the requisite alternate lifting and dropping of the monkey, a second monkey within the tubular member and immediately behind the nose of the same. 70

6. For driving tubular structures into the soil the combination of, a tubular member, a tapered nose at the lower end thereof having driving connection with the tubular member, a frame on the top of the tubular member carrying a depending fixed piston the rod of which is hollow, a hollow monkey constituting a working cylinder for the piston and guided to slide vertically thereon, the working chamber being provided between the upper side of the piston and the underside of the hollow interior of the monkey, means for admitting steam down the hollow piston-rod to the working cylinder through orifices provided at the piston 80 end, a second monkey mounted within the tubular member immediately behind the nose of the same, and non-rigid means, having in itself a comparatively small inertia effect, connecting the lower monkey to the upper monkey, whereby the lower monkey is made to follow the movements of the upper monkey. 85

7. For driving tubular structures into the soil the combination of, a tubular member, a tapered nose at the lower end thereof having driving connection with the tubular member, a frame on the top of the tubular member carrying a depending fixed piston the rod of which is hollow, a hollow monkey constituting a working cylinder for the piston and guided to slide vertically thereon the working chamber being provided between the upper side of the piston and the underside of the hollow interior of the monkey, means for admitting steam down the hollow piston-rod to the working cylinder through orifices provided at the piston end, a second monkey mounted within the tubular member immediately behind the nose of the same, and a double flexible connection extending from the upper monkey one portion on each side of the cylinder of the same down to the lower monkey with which it has operative connection so that the lower 100 monkey follows the movements of the upper monkey. 110

8. For driving tubular structures into the soil the combination of, a tubular member, a tapered nose at the lower end thereof having driving connection with the tubular member, a frame on the top of the tubular member carrying a depending fixed piston, the rod of which is hollow, a hollow monkey constituting a working cylinder for the piston and guided to slide vertically thereon, the working chamber being provided between the upper side of the piston and the underside of the hollow interior of the monkey, means 120 for admitting steam down the hollow piston-rod to the working cylinder through orifices provided at the piston end, a second monkey mounted within the tubular member immediately behind the nose of the same, and a double flexible connection extending from the upper monkey one portion on each side of the cylinder of the same down to the lower monkey with which it has operative connection so that the lower 125 monkey follows the movements of the upper monkey. 130

ton-rod to the working cylinder through orifices provided at the piston end, a second monkey mounted within the tubular member immediately behind the nose of the same, and a flexible connection between the upper and lower monkeys whereof one end is secured to the upper monkey to one side of the working cylinder and the other end extends down, passes under a pulley on the 10 lower monkey and thence up to the other side of the working cylinder where it is secured to the upper monkey.

9. For driving tubular structures into the soil the combination of, a tubular member, 15 a tapered nose at the lower end thereof having driving connection with the tubular member, a frame on the top of the tubular member carrying a depending fixed piston the rod of which is hollow, a hollow monkey 20 constituting a working cylinder for the piston and guided to slide vertically thereon, the working chamber being provided be-

tween the upper side of the piston and the underside of the hollow interior of the monkey, means for admitting steam down the 25 hollow piston-rod to the working cylinder through orifices provided at the piston end, a second monkey mounted within the tubular member immediately behind the nose of the same, two vertically disposed rods extending through the upper monkey on opposite sides of the cylinder of the same said rods being screw-threaded at the upper ends and having threaded on them nuts and springs operating between the nuts and the 30 monkey for adjustment and a flexible connection extending from one end of one rod within the tubular member down to the lower monkey where it passes under a pulley on the same and up to the other rod to 40 whose lower end it is secured.

In testimony whereof I affix my signature.

ALEXANDER GEORGIEVITCH ROTINOFF.
